MUFFLER ATTACHMENT FOR TELEPHONES

Filed April 6, 1925

Fig. 1

Fig. 2.

Inventor:
Francis J. Strobel,
by his Attorneys,
Dawson & Dawson.

UNITED STATES PATENT OFFICE.

FRANCIS J. STROBEL, OF PHILADELPHIA, PENNSYLVANIA.

MUFFLER ATTACHMENT FOR TELEPHONES.

Application filed April 6, 1925. Serial No. 21,113.

This invention relates to that type of device known as a desk booth adapted for attachment to a telephone instrument and so formed as to enable an operator to use 5 the telephone without being overheard by others in the immediate neighborhood.

The principal object of the invention is to provide an attachment of this type which while compact and comparatively light in 10 weight possesses in full degree the expansion chamber which is a requisite in these devices for properly modifying the sounds entering the instrument.

A further object of the invention is to provide novel means for attaching the device 15 to the standard telephone instrument.

A still further object of the invention is to provide a novel absorption pad for assisting in the proper modulation of the 20 sound waves prior to their entering the transmitter of the telephone.

The invention further contemplates the provision of a novel mouthpiece construction as hereinafter described.

25 These and other advantageous ends I obtain by means of a construction such as illustrated in the attached drawings, in which:

Figure 1 is a partial sectional view showing a device made in accordance with my 30 invention as applied to a standard telephone instrument, and

Fig. 2 is a front view of the device.

With reference to the drawings, the 35 device comprises a hollow casing 1 having in its forward face an opening 2 surrounded by an outwardly projecting flange 3. The flange 3 is provided with means for detachably securing thereto a mouthpiece 4 of well 40 known type constructed so as to entirely embrace the mouth of one using the telephone instrument to which this device is adapted to be attached, the said mouthpiece being in the present instance threaded into the outer end of the flange 3.

The casing has extending inwardly from the rear or opposite side a recess 5 formed to receive the transmitting head 6 of a standard telephone instrument. The recess 50 5 is flanged inwardly at the bottom as indicated at 7, and arms 13 extend radially inwardly from the flange and attach at their inner ends to a ring 14. This ring 14, when the device is applied to the telephone instrument, registers with the mouth of the latter. The flange 7, arms 13, and ring 14

support in the bottom of the recess 5 a pad 9 of material, such as felt or sponge rubber, which may be compressed to some extent and which has marked sound absorptive qualities. Felt has been used as absorptive pads in devices of this general character, but so far as I am aware, the use of sponge rubber pads is novel with me, and this material has marked advantages over 60 felt and similar substances, both as to cheapness and sanitation. The rubber also is particularly well suited for use in my device, since this pad assists in holding the attachment in place upon the telephone instrument. 70

As shown in Fig. 2, I place on the recessed side of the casing two sets of perforated lugs 10, 10 and 11, 11, these lugs being placed in alignment, as well illustrated, and being adapted for reception of a retaining element 12 which in the present instance takes the form of a wire of inverted U-shape. With the attachment placed over the transmitting head 6 of the instrument as 80 shown in Fig. 1, this retaining element 12 is inserted through the lugs as clearly illustrated in Fig. 2, and by engagement with the back of the transmitting head prevents dislodgment of the attachment from the 85 telephone instrument. The parts are so proportioned that in order to permit insertion of the element 12 through the lugs 10 and 11, the pad 9 must be compressed to a certain extent, thereby making the connection 90 between the attachment and the transmitting head a firm one. As will be apparent, the pad 9 also functions to seal the joint between the walls of the recess 5 and the transmitting head. 95

It will be noted that the construction as herein described provides a chamber in the interior of the casing which extends not only in front of the transmitting head but also completely around its periphery, and 100 that without materially increasing the overall size of the attachment I obtain an expansion chamber which is ample to modify the tones of one speaking into the transmitter. 105

As shown, the casing is rounded out or convexed at the periphery, and this not only adds to the general appearance of the device, but affords better results by eliminating sharp corners and other obstructions. 110

The detachable nature of the mouthpiece is also of importance, since it provides for

the removal of the mouthpiece by those objecting to its use by others than themselves, and by providing the flange 3 to which the mouthpiece is normally attached, I form an auxiliary mouthpiece which while not of the mouth-embracing type is still sufficient to enable efficient use of the instrument even after the mouthpiece 4 has been removed.

Furthermore, by the use of an attaching means such as I have described and including the element 12 which engages the back of the transmitting head 6, I avoid the possibility of marring the telephone instrument, and the securing element 12 is capable of removal by a single movement when it is desired to remove the attachment from the telephone.

Although I prefer to remove the normal mouthpiece of the telephone instrument when attaching my device, it will be understood that this is not essential, although where the telephone mouthpiece is left in place, it is desirable to increase the depth of the attachment sufficiently to provide for a free circulation of the sound waves through the interior chamber of the casing.

I claim:

1. A telephone attachment comprising a casing adapted for reception of the transmitting head of a standard telephone instrument, said casing having a rear wall contiguous with the rear wall of said trans-

mitting head and extending in a plane common to both, and front and side walls spaced apart from the respective walls of said head, whereby a sound chamber is formed completely around the periphery of said head and to the front thereof; and a mouth piece on said front wall adapted to entirely embrace the mouth of a person using said instrument.

2. A telephone attachment comprising a casing having rear, front and side walls forming a sound chamber; a recess formed in said rear wall, for the reception of the transmitting head of a standard telephone instrument, whereby the rear wall of the casing and that of the transmitter are contiguous and extend in a plane common to both and the sound chamber is formed completely around the periphery of the transmitter and to the front thereof; an inturned flange on the inner end of said recess, forming an opening adapted to register with the mouth of said transmitting head; a compressible element confined between and engaged by the said flange and the face of said transmitter; means on the casing adapted to engage the back of the transmitting head for retaining the casing in position thereon; and a mouth piece attached to said casing and communicating with said sound chamber.

FRANCIS J. STROBEL.
